(57) **CLAIM**

The ornamental design for an abdominal exercise machine, as shown and described herein.

DESCRIPTION

FIG. 1. Is a perspective view of my abdominal exercise machine;

FIG. 2. Is a side elevational view thereof; the reverse side elevational view being identical thereto;

FIG. 3. Is a front view thereof;

FIG. 4. Is a rear view thereof;

FIG. 5. Is a top plan view thereof; and,

FIG. 6. is a bottom view thereof.

The broken line showing portions of the drawings are for illustrative purposes only and form no part of the claimed design.
